UNITED STATES PATENT OFFICE.

CHARLES SULFER, OF MILWAUKEE, WISCONSIN, ASSIGNOR TO DIAL CASH REGISTER COMPANY, OF MILWAUKEE, WISCONSIN, A CORPORATION OF ARIZONA.

SALES-INDICATOR FOR CASH-REGISTERS.

1,135,554.

Specification of Letters Patent.

Patented Apr. 13, 1915.

Application filed August 21, 1909. Serial No. 514,048.

To all whom it may concern:

Be it known that I, CHARLES SULFER, a citizen of the United States, and a resident of the city of Milwaukee, in the county of Milwaukee and State of Wisconsin, have invented certain new and useful Improvements in Sales-Indicators for Cash-Registers; and I do hereby declare that the following is a full, clear, and exact description 5 of the same, reference being had to the accompanying drawings, and to the numerals of reference marked thereon, which form a part of this specification.

This invention relates to indicators for 15 that class of cash registers in which each sale or transaction is correctly indicated by the machine to the customer and is shown in connection with cash registers of the type set forth in my prior application for patent 20 filed on the 29th day of December, 1906, Serial No. 350,057, in which the registering is accomplished by the co-action of rotating elements operated from a suitable dial, although, of course, adaptable for use in any 25 type or kind of cash register.

Heretofore to accomplish the desired result, namely, to project into view a tablet or card bearing a character, figure or number corresponding with the sale, complicated 30 mechanism has been required, adding greatly to the cost of the machine, and, owing to the complicated structure, frequently getting out of order and necessitating repairs. Furthermore, where co-acting levers are utilized for 35 this purpose frequently very slight wear of the parts is sufficient to permit the wrong indicator card to be brought into view, thus enabling a dishonest clerk to register one number while indicating another to the pur- 40 chaser. So too, in mechanisms heretofore used it has been sometimes possible to so operate the register as to throw an indicator into view to indicate a sale of a larger amount than that registered and this has 45 resulted in loss to the owner. In most of the devices heretofore constructed for the purpose, inaccuracies are possible without intent and frequently may be easily effected by the skilful operator to the end of de- 50 frauding his employer.

The object of this invention is to afford an absolutely positive construction in which the sum registered by the actuation of the suitable element on the keyboard must in- 55 evitably be correctly indicated to the cus- tomer.

It is also an object of the invention to afford a positively acting mechanism for the purpose described and of the utmost simplicity and so constructed as to require minimum power in operation and to be practically noiseless. 60

It is an object also of the invention to afford in a cash register an indicating device operating wholly by rotation and opera- 65 tively connected to respond to each movement on the keyboard in registering and to automatically return to neutral at the beginning of the next succeeding register.

It is also an object of the invention to 70 afford in connection with a cash register operated by rotative elements an indicating device also rotative and positively geared to the rotative actuating mechanism for the recorder thereby insuring absolute accuracy 75 in both the recorder and the indicator.

Finally it is an object of the invention to reduce previous constructions to the utmost simplicity and by such simplicity of construction to enable the price of the product 80 to be reduced to a mere fraction of that heretofore demanded by the manufacturers of cash registers.

The invention consists in the matters hereinafter described and more fully pointed out 85 and defined in the appended claims.

In the drawings: Figure 1 is a front elevation of a cash register such as set forth in my prior application for patent above mentioned, provided with a device embodying my invention. Fig. 2 is a central vertical section taken longitudinally of the dial shafts and showing the shafts and dials in elevation. Fig. 3 is a view partly in section and partly in elevation of the dials showing the same removed from the machine. Fig. 4 is an enlarged fragmentary section taken on the dial. Fig. 5 is a section on line 5—5 of Fig. 2. Fig. 6 is a section on line 6—6 of Fig. 2. Fig. 7 is a section on line 7—7 of Fig. 2. Fig. 8 is a section on line 8—8 of Fig. 2. Fig. 9 is a fragmentary top plan view of the indicator casting and the indicators therein, showing the same removed from the machine. Figs. 10, 100 105 11 and 12, are face views of the printed or stamped figure strips which are secured on the indicating dials or wheels to indicate the purchase. Fig. 13 is a view taken longitudinally of the transmission shafts for the indicators showing the innermost in elevation. Fig. 14 is a reduced fragmentary sec- 110

tion of the inner ends of the master or dial shafts.

As shown in the drawings: Said machine
5 embraces a casing 1, which may be con-
structed of cast metal or in any suitable
manner or material, and comprises side, top
and rear walls, and in the bottom of which
is a money drawer indicated by 2. Mounted
10 upon the base (in which is the money drawer
before described) is an interior frame con-
sisting of a front plate 3, and a back plate 4,
and a bottom brace bar or plate 5, as shown in
Fig. 2, and journaled in said front and back
15 plates 3 and 4, and arranged concentrically
is a central actuating shaft 6, a dollar shaft
7, a dime shaft 8, and a penny or cents shaft
9, the last three named of which are, of
course, tubular, the one fitted in the other
20 and through the innermost of which ex-
tends the actuating shaft 6, the inner end of
which is journaled in the rear plate 4. The
outer end of the shaft 6, and consequently
also the outer ends of the shafts 7, 8, and 9,
25 are supported on a standard 10, secured to
the face of the machine and secured on the
outer end of said shaft 6, is a crank 11. Se-
cured upon each of the shafts 6, 7, 8, and 9,
preferably at the inner end of each is a
30 spiral spring 80, at all times under tension
on the respective shaft and which im-
mediately acts to return the shafts to nor-
mal, as shown in Fig. 1, after each actua-
tion of the machine. The inner end of each
35 spring 80, may be secured to the respective
shaft or gear wheel on the shaft and the
outer ends thereof are secured on a shaft or
rod 82, extending parallel the concentric
shafts as shown in Fig. 5.

Secured on the respective shafts 7, 8, and
40 9, are concentric dials 13, 14, and 15, re-
spectively, and slidably secured in each of
said dials at equal distances apart on the
same dial are push pins 83, 84, and 85, and
45 on the respective dollar, dimes and cents
dials, and the innermost and outermost of
which are marked consecutively and up-
wardly from the standard 10, with the sig-
nificant digits to indicate respectively dol-
lars and cents, the cents dial having also a
50 push pin 20, thereon marked "No sale."

The intermediate dial or that for dimes is
marked consecutively by tens and upwardly
from the standard. On all the dials the
55 push pins are arranged on a semi-circum-
ference on the right side of the standard, as
shown in Fig. 1.

Release push pins are provided on the
respective dials on the left side the standard
indicated respectively by 21, 22, and 23.
60 Each of said dials, as shown, is constructed
of sheet metal to afford an annular cham-
ber within the same in which is yieldingly
supported a retaining ring 25, 26, and 27
respectively, which are provided with ap-
65 pertures 16, 17 and 18, respectively, to re-

ceive and engage a detent 28, on the inner
end of each of the push pins when the same
is pressed inwardly, and as shown, each of
the push pins is provided on its outer side
or that directed toward the periphery of the
70 dial with a slot or notch which normally lies
outside of the surface of the dial, as indi-
cated in the push pin 83, in Fig. 4, but
which, when the push pin is pressed in-
wardly, and its detent engaged in the re-
taining ring, lies within the dial as indicated
75 by the push pin 17, in said figure. The lever
11, is also provided with dependent in-
wardly directed brackets 12, one for each
set of push pins on the respective dials so
that if one or more of the push pins are
80 pressed inwardly on the different dials, said
brackets on said lever of necessity engage
against the same to actuate said dials when
the lever is swung to right and downwardly
85 to the standard 10, thus rotating the dial a
distance dependent upon the push pin en-
gaged. All the foregoing is clearly set
forth in my prior application for patent
filed on the 2nd day of August, 1909, Se-
90 rial No. 510,850.

The release pins 21, 22 and 23, and the
"No sale" pin 20, when pressed inwardly
95 on the respective dials act to instantly re-
lease any keys previously depressed and the
said release keys 21, 22 and 23, being beyond
the sweep of the lever, of course, serve but to
release previously actuated push pins and
can at no time be engaged by the actuating
100 lever.

On the inner end of each of the shafts 7,
8, and 9, is rigidly secured a spur gear 81,
and journaled in the back plate 4, and in a
suitable bracket 29, secured in the top of the
casing are nested or co-axial shafts 30, 31
105 and 32, on each of which at the forward end
is secured a miter gear 33, 34, and 35, re-
spectively, which mesh with corresponding
miter gears 36, 37, and 38, secured respec-
tively on the vertically journaled co-axial
110 shafts 39, 40, and 41, which extend up-
wardly through the top of the casing and on
which are secured respectively the indicating
wheels or dials 42, 43, and 44, each com-
prising a pressed metal wheel or dial on the
115 peripheral flange of which is secured num-
bers corresponding with the numbers on the
keyboards dials, that is to say, the lower of
said indicating wheels or dials which cor-
responds with the cents keyboard dial is
120 marked with the significant digits and with
the words "No sale," said digits being re-
peated in each semi-circumference of the
dial.

The intermediate dial or that appropriated
125 to dimes is similarly marked from ten to
90, inclusive, said numbers being repeated
on each semi-circumference, and in a like
manner the upper or that appropriated to
dollars or corresponding to the dollar key-
130

board dial is marked with the significant digits to correspond with the significant digits on the keyboard dial for dollars. Rotatably secured on each of said transmission shafts 5, 30, 31, and 32, is a spur gear 45, 46, and 47 respectively. In each instance a spring pawl 48, is secured on said gear and engages a ratchet wheel 49, rigidly secured on the respective shafts, that shown in Fig. 5, being 10 secured on the pennies shaft, and as shown, a spring 50, is engaged on said gear to engage the pawl and acts to hold the same in engagement with the ratchet so that as the shaft rotates in one direction in recording 15 exactly the same rotational movement is effected in the corresponding indicating dial, inasmuch as the intermeshing gears are all of the same size and in consequence, the number shown on the push pin from which 20 the key board dial is actuated must inevitably appear in the view aperture 51, in the indicator casing 52, at the top of the machine.

Means are provided for releasing the indicator dials and to return the same to 25 neutral. For this purpose, as shown, a shaft 53, is journaled above the gears 45, 46, and 47, and is provided at its rear end with a dependent arm 54, which extends somewhat 30 below the periphery of a wheel 55, on the inner extremity of the crank shaft 6. Secured on said wheel or disk is a pin 56, adapted to engage said depending arm or 35 lever 54, to actuate the same, as shown in dotted lines in Fig. 7, and secured on said shaft 53, are laterally directed arms 57, each of which is provided with a pin 58, which extends laterally therefrom into position to engage the extended tails of the 40 detents or pawls 48, as shown in Figs. 5 and 6, to lift the pawl from the ratchet.

Rigidly secured at the inner end of the respective shafts 30, 31 and 32, are spiral pulling springs 59, the other end of which is 45 secured to the top plate 60, to exert at all times a sufficient tension on each of the shafts to rotate the same back to neutral after each actuation from the dial shafts.

The recording mechanism is actuated from 50 the same master gear wheels 81, on the respective dial shafts and may be either as set forth in my prior application for patent hereinbefore mentioned or may be of any other type or character of recording mechanism suitable for the purpose. All such mechanism, however, has been omitted from the drawings and specification in this case as they form no essential part of this invention, and it is to be understood that the 55 mechanism or any part thereof may be used in connection with any suitable recording mechanism howsoever actuated.

The operation is as follows: Inasmuch as 60 there is a front and rear view aperture in 65 the casing for the indicators, it follows that

the readings on the periphery of each of said indicating dials must correspond on each semi-circumference when it is desired to ring up a sale, as, for instance, Three Dollars, Seventy Five Cents, the three push pin 70 on the dollar dial, the 70 push pin on the dimes dial, and the 5 push pin on the pennies dial are all pressed inwardly until the detents 28, engage the shifting or detaining rings, thus holding the said push pins inwardly. The actuating lever 11, is now 75 swung about the semi-circumference of the dials and the bracket on said lever first engages the 5 push pin on the dollar, then the 70 push pin on the dimes, and the 5 push pin 80 on the cents, and rotate said dials until said push pins are brought to the standard 10, whereupon the lever being released, the actuating dials return to normal. This rotational movement of the respective dials, 85 of course, is communicated through the master gears 81, to any suitable recording mechanism for registering the amounts indicated thereon and also through the medium of said master gears, the gears 45, 46, 90 and 47, are rotated reversely, thus drawing the pawls around the ratchets and without rotating the respective shafts 30, 31 and 32, or the indicating dials. When the limit of 95 forward rotational movement of the dials has been reached, however, in recording the springs 80, return the dials to normal which acts to rotate said gears and, of course, the respective dial shafts through the medium of the gears 81, in the opposite direction. 100 This immediately brings the pawls 48, into positive engagement with the ratchets on the respective shafts and in consequence, the shafts 30, 31 and 32, are rotated reversely from the preliminary rotation of said gears, 105 these in turn rotating the indicating dials, such rotational movement of the indicating dials being exactly equal to the rotational movement of the dials in returning to normal and the tension of the springs 59 is increased. 110 In consequence, when the dials again come to rest at normal, the indicating dials also come to rest indicating in the view apertures in its casing the same identical numbers in dollars, dimes and cents corresponding with the push pins previously 115 actuated. Under the conjoint action of the pawls and springs, said indicating dials are firmly held in indicating position for the amount last registered until the register is 120 next actuated whereupon the preliminary movement of the actuating lever brings the pin 56, in contact with the lever or arm 54, thereby clearing or lifting the pawls adapting the springs 59, to return the indicators 125 to normal prior to the reverse rotation of the actuating dials to permit repetition of the action.

Of course, it is to be understood that I 130 have shown but one convenient means of

embodying my invention, for obviously various mechanism may be employed to actuate the indicating dials to correspond with the movement of the keyboard dials and the shafts therefor in recording. I therefore do not purpose limiting this patent otherwise than necessitated by the prior art, for obviously many details of construction may be varied and any desired part of the recording mechanism may be employed in connection with my invention without departing from the principle thereof.

I claim as my invention:

1. In a cash register the combination with interfitting, concentric rotating actuating dials marked to denote different money denominations of rotating indicating dials marked to correspond with the actuating dials and to indicate the sum or sums to be registered and operative connections to actuate the indicating dials from the actuating dials to correspond with the amounts to be registered.
2. In a machine of the class described a keyboard, comprising interfitting rotatable dials, keys secured thereto, a lever for operating all of the dials by engaging the proper keys, rotative indicating dials marked to indicate each a separate money denomination, and operative connections actuated with the keyboard to rotate said dials.
3. A machine of the class described embracing a plurality of substantially horizontally journaled indicating dials, concentric interfitting actuating dials and geared connections operated by the actuating dials for actuating the indicating dials to indicate the amounts registered.
4. An indicator for cash registers embracing rotative indicating dials, numerals consecutively marked on each semi-circumference thereof, and rotatable means operated in registering for rotating the dials to bring the amounts registered and indicated on such dials into vertical alinement.
5. A machine of the class described embracing a plurality of concentric interfitting master rotating elements, each adapted to move in registering a distance proportionate to the amount to be registered thereby, a single lever for selectively rotating one of said elements or any combination of said elements, shafts actuated therefrom and indicating wheels on said shafts each marked to represent a particular denomination and rotated correspondingly in return direction with the respective master elements to indicate the individual sale.
6. A machine of the class described embracing a key board comprising a plurality of master rotating elements each adapted to move in registering a distance proportionate to the amount to be registered thereby, a single element for rotating one or any combination of said master rotating elements,

shafts actuated therefrom, indicating wheels on said shafts each marked to represent a particular denomination, and rotated correspondingly with the respective master elements, a casing inclosing the indicating wheels and view apertures therein in vertical alinement through which the amount to be registered may be read.

7. In a machine of the class described a casing, a keyboard comprising a plurality of concentrically arranged rotative dials, axially alined shafts for said dials, a master gear on each shaft, a gear meshing with each master gear and individual sales indicating dials driven by said gears as said keyboard dials return to normal a distance to correspond with the recording travel of the keyboard dials.

8. In a machine of the class described a casing, a keyboard comprising a plurality of concentrically arranged rotative dials, axially alined shafts for said dials, a master gear on each shaft, a gear meshing with each master gear, indicating dials driven by said gears a distance to correspond with the recording travel of the keyboard dials and a release means for permitting the indicating dials to return to normal.

9. In a machine of the class described the combination with concentric interfitting rotative actuating dials, of rotative indicating dials and operative connections between each indicating dial and one of said interfitting dials whereby the indicating dial is rotated with the respective actuating dial, as said actuating dial rotates reversely to its normal position.

10. In a machine of the class described the combination with concentric interfitting rotative elements adapted to be actuated in registering, of gears driven thereby, shafts journaled adjacent said gears, gears of like size thereon meshing with the first named gears, indicating dials operated from said shafts as the rotative elements return to normal, springs positively engaged on said shafts, and acting to return the same to normal after each actuation.

11. In a device of the class described the combination with concentric rotative interfitting key board dials, an equal number of indicating dials positively driven therefrom, and marked to correspond therewith, operative connections for actuating the same to indicating position as the key board dials return to normal, and a trip mechanism for returning the indicating dials to normal when the key board dials are next actuated.

12. In a machine of the class described co-axial shafts, an actuating keyboard dial on the outer end of each, a master gear secured on each shaft, co-axial nested shafts adjacent the first named shafts, gears rotative thereon of equal size with the master gears, a pawl secured on each gear, a ratchet on each

of the last named shafts, and adapted to be engaged by the pawl, a spring acting to return each mechanism to normal, and a trip lever for releasing the indicating mechanism 5 at the beginning of the next succeeding count.

13. In a cash register vertical actuating dials, horizontal indicating dials adapted to coact to exhibit the amount of each sale in a 10 vertical column, an independent mechanism for operating each indicating dial from the appropriate actuating dial, as the indicating dial returns to normal and mechanisms for returning the indicating dials to normal released by the forward rotation of the actuating dials.

14. In a cash register actuating dials, concentric dial shafts actuated thereby, concentric transmission shafts, intermeshing gears 20 connecting the appropriate shafts, vertical concentric indicating shafts, intermeshing bevel gears connecting the appropriate transmission and indicating shafts and indicating dials on said indicating shafts adapted to be actuated by the return rotation of 25 said actuating dials to indicate the sum of each sale.

15. In a cash register actuating dials, concentric dial shafts actuated thereby, concentric transmission shafts, intermeshing gears 30 connecting the appropriate shafts, vertical concentric indicating shafts, intermeshing bevel gears connecting the appropriate transmission and indicating shafts, indicating dials on said indicating shafts and a mechanism on each transmission shaft for returning the respective indicating dial to normal after each actuation thereof.

16. In a cash register concentric dials, concentric dial shafts operated by the dials, concentric transmission shafts, concentric indicator shafts, gears connecting the shafts whereby the indicating shafts rotate proportionally to the dial shafts, indicating wheels 40 on said indicating shafts and means adapted to return the indicating dials to normal as the actuating dials are rotated forwardly.

17. In a cash register concentric dials, concentric dial shafts operated by the dials, 50 concentric transmission shafts, concentric indicator shafts, gears connecting the shafts whereby the indicating shafts rotate proportionally to the dial shafts, indicating wheels on said indicating shafts, a spring for returning each dial shaft to normal and a spring for returning each indicator to normal.

18. In a cash register concentric rotating actuating dials, shafts operated thereby, 60 transmission shafts parallel therewith, vertical indicator shafts, gears connecting said shafts, all of said gears of a size to rotate the indicator shafts equally with the dial shafts, indicating wheels secured to the indicating shafts arranged in vertical aline-

ment adapted to be moved to indicating position as the actuating dials return to normal, and means adapted to permit the indicating dials to return to normal as said actuating dials are rotated forwardly. 70

19. In a cash register concentric rotating actuating dials, shafts operated thereby, transmission shafts parallel therewith, vertical indicator shafts, gears connecting said shafts, all of said gears of a size to rotate 75 the indicator shafts equally with the dial shafts, indicating wheels secured to the indicating shafts arranged in vertical alinement, ratchet wheels on the transmission shafts, pawls carried by the gears on the transmission shafts engaging the ratchet wheels, and means for releasing the pawls from the ratchet wheels to permit the indicating wheels to return to normal as the actuating dials are rotated forward. 80

20. In a cash register actuating dials, dial shafts connected therewith, transmission shafts, gears rigidly secured on the dial shafts, gears journaled on the transmission shafts meshing with the gears on the dial shafts, indicator shafts, intermeshing gears on the indicator and transmission shafts, indicating wheels adapted to be actuated to indicating position as said actuating dials return to normal position, and means adapted to return said indicating dials to normal 90 as said actuating dials move forwardly on the indicator shafts marked to denote money denominations. 95

21. In a cash register actuating dials, dial shafts connected therewith, transmission shafts, gears rigidly secured on the dial shafts, gears journaled on the transmission shafts meshing with the gears on the dial shafts, indicator shafts, intermeshing gears 100 on the indicator and transmission shafts, indicating wheels on the indicator shafts marked to denote money denominations, a ratchet wheel rigidly secured on each transmission shaft, a pawl connecting the respective gear and ratchet wheels, a spring connected to each transmission shaft adapted to return each indicator shaft to normal, a rock shaft extending parallel the transmission shafts and means thereon for releasing 105 the pawls. 110

22. In a device of the class described concentric, interfitting actuating dials, concentric indicating dials, independent mechanisms connected with the respective actuating dials adapted to adjust the indicating dials equally with the actuating dials, and means controlled by the rotation of the actuating dials for releasing part of the mechanism to return the indicating dials to 115 normal. 120

23. In a device of the class described concentric, interfitting actuating dials, concentric indicating dials, independent mechanism connected with the respective actuat- 130

- ing dials adapted to adjust the indicating dials equally with the actuating dials, means controlled by the rotation of the actuating dials for releasing part of the mechanism to return the indicating dials to normal on the forward rotation of the actuating dials adapting said indicating dials to be rotated to indicate the amount by the actuating dials when rotating reversely.
- 10 24. In a device of the class described concentric, interfitting dials marked with numerals, indicating dials marked with numerals to correspond with the interfitting dials, rotary mechanism connecting the interfitting dials and the indicating dials, and a mechanism for controlling the operation of the indicating dials adapted to release part of the rotary mechanism to permit the indicating dials returning to normal.
- 15 25. In a device of the class described concentric, interfitting rotatable actuating dials, concentric indicating wheels above the same, concentric shafts, equal sized gears connecting the shafts to operate the indicating wheels by rotation of the actuating dials, and a mechanism for controlling the connection between one set of gears and their shafts for releasing the gears to permit the indicating wheels to return to normal.
- 20 26. In a device of the class described concentric dials, keys secured thereto, a rotary actuating element for engaging the keys and rotating the respective dials, indicating wheels, independent mechanisms, one connecting each dial with the respective wheel and a release mechanism for disconnecting each independent mechanism permitting the indicating wheels returning to normal after each actuation.
- 25 27. In a sales indicating machine vertically rotatable actuating dials, horizontally rotatable indicating dials, gears and shafts connecting the dials to rotate the indicating dials equally with the actuating dials as said actuating dials return to normal position after being actuated.
- 30 28. In a device of the class described indicating and actuating dials disposed in planes at right angles to each other and a mechanism actuated by the return rotation of the actuating dials in one plane to rotate the indicating dials in the other plane.
- 35 29. In a device of the class described actuating dials, concentric shafts connected thereto, concentric transmission shafts, indicating dials, concentric shafts connected thereto, spur gears connecting one set of shafts with the transmission shaft and bevel gears connecting the other set of shafts with the transmission shafts.
- 40 30. In a device of the class described concentric actuating dials, concentric shafts connected thereto, indicating dials, concentric shafts connected thereto and a transmission mechanism between the two sets of
- shafts for actuating one set of shafts with the other in one direction only.
- 45 31. In a device of the class described actuating dials, indicating dials and a mechanism connecting the same whereby the actuating dials operate the indicating dials to indicating position when they rotate reversely to normal position.
- 50 32. In a device of the class described actuating dials, indicating dials, independent mechanisms connecting the dials adapting the dials to rotate together on the return rotation of the actuating dials, and springs for rotating the indicating dials to normal when the actuating dials are rotated forwardly.
- 55 33. In a device of the class described horizontal indicating wheels, springs for actuating the dials in one direction, vertical actuating dials, and a transmission mechanism actuated thereby for actuating the indicating dials in one direction and setting the tension on the springs to actuate the dials reversely.
- 60 34. In a device of the class described actuating dials, indicating dials, shafts connected with said dials, gears on said shafts, and a transmission mechanism between the shafts comprising transmission shafts, gears loosely journaled thereon in mesh with the gears on the actuating shafts, gears rigid on said shaft in mesh with the gears on the indicating shafts, and a clutch for each loose gear on the transmission shafts for connecting the same with the respective shaft and for releasing the same from the respective shaft.
- 65 35. In a device of the class described horizontal indicating wheels, springs for actuating the dials in one direction, vertical actuating dials, a transmission mechanism actuated thereby for actuating the indicating dials in one direction and setting the tension on the springs to actuate the dials reversely, and mechanism for actuating a part of the transmission mechanism to release the springs.
- 70 36. In a device of the class described actuating dials, indicating dials, shafts connected with said dials, gears on said shafts, a transmission mechanism between the shafts comprising transmission shaft, gears loosely journaled thereon in mesh with the gears on the actuating shafts, gears rigid on said shaft in mesh with the gears on the indicating shafts, a clutch for each loose gear on the transmission shafts for connecting the same with the respective shaft and for releasing the same from the respective shaft, mechanism for actuating the clutches to couple the gears to the shaft when the actuating dials rotate in one direction thereby imparting rotation to the indicating dials equal to the rotation of the actuating dials, mechanism for actuating the clutches to re-

lease the gears, and springs for returning the indicating dials to normal.

37. In a device of the class described actuating dials, shafts driven thereby, indicating dials, shafts connected thereto, gears on said shafts, transmission shafts, sets of gears thereon meshing with the gears on the aforesaid shafts, one of said sets of gears being loose on the transmission shafts, 10 ratchet wheels rigidly secured to the transmission shafts, and a spring pressed pawl pivoted on each loose gear and engaging one of the ratchet wheels.

38. In a device of the class described actuating dials, shafts driven thereby, indicating dials, shafts connected thereto, gears on said shafts, transmission shafts, sets of gears thereon meshing with the gears on the aforesaid shafts, one of said sets of gears 20 being loose on the transmission shafts, ratchet wheels rigidly secured to the transmission shafts, a spring pressed pawl pivoted on each loose gear and engaging one of the ratchet wheels, mechanism for releasing all 25 the pawls simultaneously from the ratchet wheels permitting the indicating dials rotating independently of the actuating dials.

39. In a device of the class described rotating actuating dials, indicating dials and mechanism acting to prevent the rotation of the indicating dials when the actuating dials rotate in one direction and rotate the indicating dials to indicate the amount to be registered when the actuating dials rotate 35 oppositely to return to their normal position.

40. In a device of the class described rotating actuating dials, indicating dials, mechanism for rotating the indicating dials when the actuating dials rotate in one direction and prevent rotation of the indicating dials when the actuating dials rotate oppositely, springs for rotating the indicating dials in one direction, said springs set under tension by the actuating dials, and springs 45 for rotating the actuating dials to normal after each manual actuation.

41. In a sales indicator rotatable dials, a single lever for rotating one dial or any combination of dials and indicating wheels connected with the dials to rotate when the dials rotate in one direction to indicate the amount of the sale.

42. In a device of the class described concentric dials, concentric shafts connected thereto, concentric indicator wheels, concentric shafts connected thereto, concentric transmission shafts, gears connecting the same with the aforesaid shafts, the gears on the transmission shaft connecting the dial 55 shafts being loose, and mechanism for rigidly connecting the loose gears to the shafts automatically.

43. In a device of the class described dials, concentric shafts secured thereto, gears on 60 said shafts, indicator wheels, concentric

shafts secured thereto, gears thereon, transmission shafts, gears rigidly secured thereon meshing with the gears on the indicator shafts, gears loose on the transmission shafts meshing with the gears on the dial shafts, 70 a member rigidly secured to each transmission shaft adjacent the respective loose gear, and means connecting the same and gear to rotate together in one direction.

44. In a sales indicator rotatable dials, a single lever for rotating one dial or any combination of dials, indicating wheels connected with the dials to rotate when the dials rotate in one direction to indicate the amount of the sale, mechanism for automatically rotating the indicating wheels 80 reversely to the direction in which they are rotated by the dials thereby returning the wheels to normal, and springs connected with the dials and lever for returning the 85 same to normal.

45. In a device of the class described dials, concentric shafts secured thereto, gears on said shafts, indicator wheels, concentric shafts secured thereto, gears thereon, transmission shafts, gears rigidly secured thereon meshing with the gears on the indicator shafts, gears loose on the transmission shafts meshing with the gears on the dial shafts, a member rigidly secured to each transmission shaft adjacent the respective loose gear, means connecting the same and gear to rotate together in one direction, a shaft parallel with the transmission shaft, means thereon for engaging said connecting means 95 to release the same, a lever for actuating the dials, and coacting members connected therewith and with said parallel shaft for controlling the release of said means.

46. In a device of the class described an actuating dial, a dial shaft connected thereto, and indicating wheel, an indicating shaft connected thereto, a lever for actuating the dial, a shaft connected thereto, a transmission shaft, a gear connecting the transmission shaft and indicating shaft, a gear, connecting the transmission shaft and dial shaft, one of said gears on the transmission shaft being loose, a ratchet wheel rigid on the shaft, and a pawl on the loose gear engaging the ratchet wheel whereby the indicating shaft is actuated by rotation of the dial shaft in one direction.

47. In a device of the class described dials, concentric shafts secured thereto, gears on said shafts, indicator wheels, concentric shafts secured thereto, gears thereon, transmission shafts, gears rigidly secured thereon meshing with the gears on the indicator shafts, gears loose on the transmission shafts 120 meshing with the gears on the dial shafts, a member rigidly secured to each transmission shaft, adjacent the respective loose gear, means connecting the same and gear to rotate together, mechanism for releasing said 125 130

means, and a coiled spring connected with each shaft to operate the same when said means is released.

48. In a device of the class described an actuating dial, a dial shaft connected thereto, an indicating wheel, an indicating shaft connected thereto, a lever for actuating the dial, a shaft connected thereto, a transmission shaft, a gear connecting the transmission shaft and the indicating shaft, a gear connecting the transmission shaft and the dial shaft, one of said gears on the transmission shaft being loose, a ratchet wheel rigid on the shaft, a pawl on the loose gear engaging the ratchet wheel whereby the indicating shaft is actuated by rotation of the dial shaft in one direction, and a spring for returning the indicating shaft to normal wound up when said dial shaft is rotated in one direction.

49. In a device of the class described dials, concentric shafts secured thereto, gears on said shafts, indicator wheels, concentric shafts secured thereto, gears thereon, transmission shafts, gears rigidly secured thereon meshing with the gear on the indicator shafts, gears loose on the transmission shafts meshing with the gears on the dial shafts, a member rigidly secured to each transmission shaft adjacent the respective loose gear, means connecting the same and gear to rotate together in one direction, a shaft parallel with the transmission shaft, means thereon for engaging said connecting means to release the same, a lever for actuating the dials, coating members connected therewith and with said parallel shaft for controlling the release of said means, and a spring on each shaft except the indicating shafts for returning the dials and indicators to normal.

50. In a device of the class described dials, concentric shafts secured thereto, gears on said shafts, indicator wheels, concentric shafts secured thereto, gears thereon, transmission shafts, gears rigidly secured thereon meshing with the gears on the indicator shafts, gears loose on the transmission shafts meshing with the gears on the dial shafts, a member rigidly secured to each transmission shaft, adjacent the respective loose gear, means connecting the same and gear to rotate together, mechanism for releasing said means, a coiled spring connected with each shaft to operate the same when said means is released, springs for rotating the dials in one direction and a lever for rotating the dials in the opposite direction and also operating said releasing mechanism.

51. In a device of the class described an actuating dial, a dial shaft connected thereto, an indicating wheel, an indicating shaft connected thereto, a lever for actuating the dial, a shaft connected thereto, a transmission shaft, gears connecting the transmission and indicating shafts, gears connecting the

transmission and dial shafts, said gear on the transmission shaft being loose, a ratchet wheel rigid on the shaft, a pawl on the loose gear engaging the ratchet wheel whereby the transmission shaft is actuated by rotation of the dial shaft in one direction, a spring on the transmission shaft wound up when said shaft is rotated by the dial shaft, an oscillating shaft, an arm thereon adapted to engage the pawl to release the same and permit the spring to rotate the transmission shaft, a member secured to said oscillating shaft, and means rotatable with the lever shaft to operate the same to oscillate the oscillatable shaft.

52. In a device of the class described actuating dials, indicating dials, one for each actuating dial, a direct geared connection between each actuating dial and indicating dial to rotate the indicating dials proportionately to the rotation of the actuating dials, mechanism for holding the indicating dials in indicating position, and mechanism for actuating said mechanism to release the indicating dials when the actuating dials are operated.

53. In a sales indicator for cash registers a plurality of indicating dials, actuating dials, a geared connection between the actuating dials and indicating dials adapted to rotate the indicating dials in one direction only, and mechanism for returning the indicating dials to normal.

54. In a device of the class described concentric, interfitting rotatable actuating dials, concentric indicating wheels above the same, concentric shafts, equal sized gears connecting the shafts to operate the indicating wheels by rotation of the actuating dials, a mechanism for controlling the connection between one set of gears and their shafts for releasing the gears to permit the indicating wheels to return to normal, and means operated by the rotation of the dials for operating said controlling mechanism.

55. In a device of the class described concentric interfitting actuating dials, concentric indicating dials rotatable therewith in one direction and mechanism for rotating the indicating dials in a reverse direction independently of the actuating dials.

56. In a sales indicating machine vertically rotatable actuating dials, horizontally rotatable indicating dials, gears and shafts connecting the dials to rotate the indicating dials in one direction equally with the actuating dials, and tension springs locked from operation when the indicating dials are indicating a sum but released to return the indicating dials to normal at the proper time.

57. In a sales indicating device concentric vertical actuating dials, concentric horizontal indicating dials, sets of concentric shafts connected with the dials, sets of gears connecting the shafts, one set of said gears be-

ing loose on the shafts and mechanism for coupling the same to or releasing the same from the shafts to control the operation of the indicating dials.

58. In a device of the class described concentric numbered indicating wheels, actuating dials bearing numerals of the same value, an independent mechanism connecting each indicating wheel and dial marked with like numerals, and a spring connected with each indicating dial adapted to return the same to normal prior to the next sum being indicated.

59. In a device of the class described indicating and actuating dials disposed in planes at right angles to each other, a mechanism actuated by the rotation of the actuating dials in one plane to rotate the indicating dials in the other plane, and means other than the actuating dials for returning all the indicating dials to normal after the same have been actuated.

60. In a device of the class described rotating concentric actuating dials having their faces flush, rotating indicating dials arranged vertically, concentric vertical shafts connected with the indicating dials, concentric horizontal shafts connected with the actuating dials, concentric transmission shafts, sets of gears connecting the shafts to rotate together, and springs for automatically returning the actuating dials to normal after each actuation.

61. In a device of the class described actuating dials, concentric shafts connected thereto, concentric transmission shafts, indicating dials, concentric shafts connected thereto, spur gears connecting one set of shafts with the transmission shaft, bevel gears connecting the other set of shafts with the transmission shafts, and springs connected to rotate the transmission shafts in one direction, thereby rotating the indicating dials.

62. In a device of the class described concentric actuating dials, concentric shafts connected thereto, indicating dials, concentric shafts connected thereto, a transmission mechanism between the two sets of shafts for actuating one set of shafts with the other in one direction only, and springs for actuating the indicating dials to normal position when the rotation of the actuating dials release the same.

63. In a device of the class described actuating dials, indicating dials and independent mechanisms connecting the dials adapting the dials to rotate together on the return rotation of the actuating dials.

64. In a device of the class described horizontal indicating wheels, springs for actuating the dials in one direction, vertical actuating dials, a transmission mechanism actuated thereby for actuating the indicating dials in one direction and setting the tension

on the springs to actuate the dials reversely, mechanism for actuating a part of the transmission mechanism to release the springs, and springs for returning the actuating dials to normal after each manual actuation.

70

65. In a device of the class described actuating dials, indicating dials, shafts connected with said dials, gears on said shafts, a transmission mechanism between the shafts comprising transmission shafts, gears loosely journaled thereon in mesh with the gears on the actuating shafts, gears rigid on said shaft in mesh with the gears on the indicating shafts, a clutch for each loose gear on the transmission shafts for connecting the same with the respective shaft and for releasing the same from the respective shaft, and mechanism for actuating the clutch to couple the gears to the shaft when the actuating dials rotate in one direction, thereby imparting rotation to the indicating dials equal to the rotation of the actuating dials.

75

66. In a device of the class described rotating actuating dials, indicating dials, mechanism for rotating the indicating dials when the actuating dials rotate in one direction and prevent rotation of the indicating dials when the actuating dials rotate oppositely, and springs for rotating the indicating dials in one direction, said springs set under tension by the actuating dials.

80

67. In a sales indicator rotatable dials, a single lever for rotating one dial or any combination of dials, indicating wheels connected with the dials to rotate when the dials rotate in one direction to indicate the amount of the sale, and mechanism for automatically rotating the indicating wheels reversely to the direction in which they are rotated by the dials, thereby returning the wheels to normal.

85

68. In a device of the class described concentric dials, concentric shafts connected thereto, concentric indicator wheels, concentric shafts connected thereto, concentric transmission shafts, gears connecting the same with the aforesaid shafts, and the gears on the transmission shaft connecting the dial shafts being loose, mechanism for rigidly connecting the loose gears to the shafts automatically, mechanism for actuating said mechanism to permit free rotation of said gears on the shaft and springs for rotating the shafts when said gears are loose.

90

69. In a device of the class described an actuating dial, a dial shaft connected thereto, an indicating wheel, an indicating shaft connected thereto, a lever for actuating the dial, a shaft connected thereto, a transmission shaft, gears connecting the transmission and indicating shafts, gears connecting the transmission and dial shafts, one of said gears on the transmission shaft being loose, a ratchet wheel rigid on the shaft, a pawl on the loose gear engaging the ratchet wheel whereby the

- transmission shaft is actuated by rotation of the dial shaft in one direction, a spring on the transmission shaft wound up when said shaft is rotated by the dial shaft, an oscillating shaft, an arm thereon adapted to engage the pawl to release the same and permit the spring to rotate the transmission shaft, a member secured to said oscillating shaft, means rotatable with the lever shaft to operate the same to oscillate the oscillatable shaft, a spring for returning the dial shaft to normal and a spring for returning the lever shaft to normal.
70. In a device of the class described actuating dials, shafts driven thereby, indicating dials, shafts connected thereto, gears on said shafts, transmission shafts, sets of gears thereon meshing with the gears on the aforesaid shafts, one of said sets of gears being loose on the transmission shafts, ratchet wheels rigidly secured to the transmission shafts, a spring pressed pawl pivoted on each loose gear and engaging one of the ratchet wheels, mechanism for releasing all the pawls simultaneously from the ratchet wheels permitting the indicating dials rotating independently of the actuating dials, and springs connected with the transmission shafts for actuating the same when the pawls are released.

71. In a device of the class described rotating concentric actuating dials having their faces flush, rotating indicating dials arranged vertically, concentric vertical shafts connected with the indicating dials, 35 concentric horizontal shafts connected with the actuating dials, concentric transmission shafts, sets of gears connecting the shafts to rotate together, springs for automatically returning the actuating dials to normal after 40 each actuation, and springs for automatically positioning the indicating dials in normal position when the actuating dials are manually operated.

72. In a sales indicator a plurality of indicating dials, actuating dials having their axes in a plane at right angles to the axes of the indicating dials, mechanism operating the indicating dials by rotation of the actuating dials in reverse direction, and means 50 automatically returning the indicating dials to normal as the actuating dials rotate forwardly.

In testimony whereof I have hereunto subscribed my name in the presence of two subscribing witnesses.

CHARLES SULFER.
